US0D1015081S

(12) **United States Design Patent** (10) **Patent No.:** **US D1,015,081 S**
(45) **Date of Patent:** **** Feb. 20, 2024**

(54) **LUNCH BOX**

(71) Applicant: **Dongguan Oumeng Houseware Products Co., Ltd**, Dongguan (CN)

(72) Inventor: **Jingsheng Xu**, Yueyang (CN)

(73) Assignee: **Dongguan Oumeng Houseware Products Co., Ltd**, Dongguan (CN)

(**) Term: **15 Years**

(21) Appl. No.: **29/817,615**

(22) Filed: **Dec. 2, 2021**

(51) LOC (14) Cl. **09-07**

(52) U.S. Cl.

USPC **D7/629; D7/605**

(58) **Field of Classification Search**

(57) **CLAIM**

The ornamental design for a lunch box, as shown and described.

DESCRIPTION

FIG. 1 is a front, left, top perspective view of a lunch box showing our new design;

FIG. 2 is a back, left, bottom perspective view thereof;

FIG. 3 is a front view thereof;

FIG. 4 is a back view thereof;

FIG. 5 is a left view thereof;

FIG. 6 is a right view thereof;

FIG. 7 is a top view thereof; and,

FIG. 8 is a bottom view thereof.

1 Claim, 8 Drawing Sheets
